UNITED STATES PATENT OFFICE.

CHRISTIAN S. LEHMAN, OF LAWN, PENNSYLVANIA.

DESIGN FOR A CIGAR-HOLDER.

SPECIFICATION forming part of Design No. 26,579, dated February 2, 1897.

Application filed December 19, 1896. Serial No. 616,345. Term of patent 7 years.

To all whom it may concern:

Be it known that I, CHRISTIAN S. LEHMAN, a citizen of the United States, residing at Lawn, in the county of Lebanon and State of Pennsylvania, have invented and produced a certain new and original Design for Cigar-Holders; and I do declare the following to be a full, clear, and exact description of the invention, such as will enable others skilled in the art to which it appertains to make and use the same.

My invention relates to a new and original design for cigar-holders; and it consists of a holder of the configuration and ornamentation shown in the accompanying drawing, in which I have illustrated my design in perspective.

The leading feature of the design comprises

two members A and B, the member A of which is formed with two semicircular portions 1 and 2, the member B with two semicircular portions 3, the diverging ends 5, and the point 6. The parts A and B are arranged at right angles to each other.

Having thus fully described my design, what I claim as new and original, and desire to secure by Letters Patent of the United States, is—

The design for a cigar-holder, as herein shown and described.

In testimony whereof I hereunto affix my signature in presence of two witnesses.

CHRISTIAN S. LEHMAN.
